UNITED STATES PATENT OFFICE.

SILAS H. RANDALL, OF WYOMING, OHIO, ASSIGNOR OF ONE-HALF TO JAMES D. RANDALL, OF SAME PLACE.

PHOTOGRAPH-BURNISHER.

SPECIFICATION forming part of Letters Patent No. 397,309, dated February 5, 1889.

Application filed July 6, 1888. Serial No. 279,191. (No model.)

To all whom it may concern:

Be it known that I, SILAS H. RANDALL, a citizen of the United States, residing at Wyoming, in the county of Hamilton and State of Ohio, have invented certain new and useful Improvements in Photograph-Burnishers; and I do hereby declare the following to be a full, clear, and exact description of the invention, such as will enable others skilled in the art to which it appertains to make and use the same.

My invention comprises a novel construction of those machines which impart a polished surface to photographs by passing them between a feed-roller and a stationary burnishing-bar, the details of the improvements being hereinafter more fully described, and pointed out in the claims.

In the annexed drawings, Figure 1 is a front elevation of a machine embodying my improvements. Fig. 2 is a plan of the same. Fig. 3 is a rear elevation of the upper portion of the machine. Fig. 4 is an end elevation thereof. Fig. 5 is a transverse section of the upper portion of the machine, said section being taken in the plane of the temper-screw *c*. Fig. 6 is an enlarged section of one of the ball-and-socket bearings that support the burnishing-bar holder.

30 A B represent the standards or end plates of the frame of the machine, which standards are united in front by a pair of longitudinal bars, C D, the upper bar, C, having a temper-screw, *c*, tapped in it, the point of said screw being in contact with the trough-shaped holder E, that carries the burnishing-bar. Holder E has at its ends lateral lugs F F', the under sides of which are provided with balls *f f'*, that bear within the sockets *c' c'* 35 of the bar C, one of said bearings being more clearly seen in Fig. 6. Furthermore, said holder has on its upper surface a longitudinal groove to admit the hard metallic burnishing-bar G, which is preferably square in 40 transverse section, and is held in place by set-screws *g*. This bar is parallel with a feed-roller, H, the periphery of which is roughened to afford an effective hold upon the back of the photograph, the ends of the roller being 45 provided with journals *h h'*, housed within

cylindrical boxes I I', capable of a limited vertical adjustment within the standards A B. This adjustment is effected by the devices seen in Fig. 4, wherein J is a set-screw bearing upon the upper surface of the box I, 55 and K is a screw pressing up against said box. L represents one or more lugs bearing against the front of this box. J' K' are the adjusting-screws of the other box, I'.

M is a crank attached to the journal *h'*. 60 *e e'* are stops on the upper surface of holder E, which stops bear against projections of the standards, as seen in Fig. 4, and thus prevent direct contact of the bar G and roller H.

When this machine is properly adjusted, 65 the screws J K and J' K' are set so as to level the feed-roller H and cause it to be exactly parallel with the burnishing-bar G, the passage between said roller and bar being regulated by the temper-screw *c*. A lamp or gas-jet is then used for heating the holder E, the vertical walls of which compel the smoke to 70 escape at its open ends. After the bar has become worn, the screws *g* are loosened, and said bar is turned over, so as to bring a new 75 surface into use, the screws being again tightened after this change has been effected.

I claim as my invention—

1. The combination, in a photograph-burnisher, of a feed-roll, H, two vertically-adjustable journal-boxes, I I', held by opposing set-screws J K J' K' against bearings L of the main frame, as herein described.

2. The combination, in a photograph-burnisher, of an adjustable burnishing-bar holder, 85 E, swung upon the main frame, and a screw, C, whereby said holder is adjusted, which screw projects from the main frame against the holder on the side of its attachments to said holder and below them, as herein described.

3. The combination, in a photograph-burnisher, of a burnisher swung upon a pair of pivots, an intermediate regulating-screw by which said burnisher is raised and lowered, 95 and a feed-roll journaled in independently vertically-adjustable boxes, the axis of said roll being normally parallel to the axis of said pivots, as herein described.

4. The combination, in a photograph-bur- 100

nisher, of a main frame, a vertically-adjustable feed-roll, a burnishing-bar, a swung burnishing-bar holder, and a screw whereby the holder is adjusted, which screw projects from 5 the main frame against said holder upon the side of its attachments to the main frame and below them, as herein described.

In testimony whereof I affix my signature in the presence of two witnesses.

SILAS H. RANDALL.

Witnesses:

JAMES H. LAYMAN,
FRANCIS B. JAMES.
